COMBINATION TOY CHEST, DESK, AND LOVE SEAT FOR CHILDREN

Meyer Greene, Oceanside, N. Y.

Application November 19, 1948, Serial No. 149,708

Term of patent 3½ years

(Cl. D34—15)

To all whom it may concern:

Be it known that I, Meyer Greene, a citizen of the United States, residing at Oceanside, in the county of Nassau and State of New York, have invented a new, original, and ornamental Design for Combination Toy Chest, Desk, and Love Seat for Children, of which the following is a specification, reference being had to the accompanying drawings, forming a part thereof.

In the drawings:

Fig. 1 is a perspective view of a combination toy chest, desk and love seat for children showing my new design.

Fig. 2 is a front perspective view thereof with the table element shown removed for convenience of illustration only.

Fig. 3 is a perspective view thereof taken slightly from the right and showing the table element when in its vertical position and usable as a blackboard. The seat is also shown partly raised.

Fig. 4 is a rear perspective view thereof, the table element being shown in reversed position so that the blackboard surface can be used by a seated child.

The characteristic features of my design are shown by means of full lines in the drawings.

I claim:

The ornamental design for a combination toy chest, desk, and love seat for children, substantially as shown and described.

MEYER GREENE.
